UNITED STATES PATENT OFFICE.

ALBERT G. MURPHY AND LOUIS L. HALBERSTADT, OF RACINE, WISCONSIN.

COMBINED GUM DISPLAY AND DISPENSING DEVICE.

1,201,331.

Specification of Letters Patent.

Patented Oct. 17, 1916.

Application filed February 26, 1915. Serial No. 10,796.

To all whom it may concern:

Be it known that we, ALBERT G. MURPHY and LOUIS L. HALBERSTADT, citizens of the United States, residing at Racine, in the 5 county of Racine and State of Wisconsin, have invented new and useful Improvements in Combined Gum Display and Dispensing Devices, of which the following is a specification.

10 The invention relates to display devices, and more particularly to the class of combined display and dispensing racks or containers.

15 The primary object of the invention is the provision of a device of this character wherein chewing gum packages will be held therein for the display of the same, and which may be singly ejected from each rack or container of the device, thus affording a unique 20 dispenser for the packages, and at the same time enabling the storage thereof in a compact manner for the display of the same.

25 Another object of the invention is the provision of a device of this character wherein the packages of gum will be held assorted, the device being readily adaptable for packages containing other goods, and which may be dispensed in single order when desired.

30 A further object of the invention is the provision of a device of this character which is simple in construction, neat and attractive for display purposes, reliable and efficient in operation, and inexpensive in manufacture.

35 With these and other objects in view, the invention consists in the construction, combination and arrangement of parts as will be hereinafter fully described, illustrated in the accompanying drawing, and pointed out in the claim hereunto appended.

40 In the drawings: Figure 1 is a side elevation of a device constructed in accordance with the invention; Fig. 2 is a vertical longitudinal sectional view through the device; Fig. 3 is a fragmentary horizontal trans- 45 verse sectional view; Fig. 4 is an enlarged fragmentary vertical sectional view through one of the containers and dispensing cups; Fig. 5 is a perspective view of one of the dispensing cups; Fig. 6 is a plan view of one 50 of the disk heads.

Similar reference characters indicate corresponding parts throughout the several views in the drawings.

55 Referring to the drawings in detail, the display and dispensing device comprises a

truncated substantially conical shaped base 10, preferably made from metal, having fitted in its bottom at intervals resilient tread members 11 to prevent the base from marking or marring the counter or other support 60 on which the device is at rest or mounted.

Secured centrally in the base 10 is the lower reduced end 12 of a vertical axle or shaft 13, which is also formed with an upper reduced end 14, and journaled upon the respective ends are upper and lower rotatable disks or heads 15 which are formed with diametrically opposed up-turned ears 16 to which are fixed in any suitable manner radially disposed substantially U-shaped 65 yokes or straps 17 supporting containers or racks hereinafter fully described.

The containers or racks are formed with four transparent walls, preferably glass panels 18, and are connected at their meeting edges in any suitable manner to form the corners of the respective containers or racks which provide chutes of substantially rectangular shape in cross section, having fitted on their upper ends removable covers or 70 tops 20, while at the lower ends of the same are discharge throats 20 in which are arranged ejector or dispensing cups 21, each formed with a pintle sleeve 22 through 75 which is passed a pintle 23, the same being engaged in the throat 20 for swingingly mounting the cup therein, one side of the cup being formed with a stop flange 24 to limit the swinging thereof in one direction, while the other side of the cup is formed with an 80 arcuate shaped guard wing 25 which closes the lower end of the chute when the cup 21 is moved to discharging position for ejecting a single package from the number thereof within the chute, as the guard wing 25 holds back the packages in the said chute when one of the same is gravitated into the cup and the latter is moving to discharging 85 position, thereby assuring the ejecting of the packages singly from the respective containers or racks.

The spindles 23 each has fixed to one end a winged nut for permitting the hand swinging of the cup for ejecting the packages from the device. The packages are introduced in the containers or racks through the upper ends on removing the covers or tops 19 therefrom, and such packages are visible 90 through the transparent walls thereof. The containers revolve in unison to bring each 105 110

thereof in convenient reach when desired for the ejecting of a single package therefrom.

From the foregoing description, taken in connection with the accompanying drawings, the construction and manner of operation of the device will be clearly understood, and therefore a more extended explanation has been omitted.

10 What is claimed is:—

A dispensing device of the character described comprising a base, a vertical shaft mounted in said base and having reduced portions, disks rotatably engaged on the re-

duced portions of the shaft and having diametrically opposed upturned ears, vertical racks forming chutes disposed next to the ears, U-shaped yokes fixed to the chutes near opposite ends thereof and detachably engaged with the ears, and dispensing means 15 located at the lower end of each chute.

In testimony whereof we affix our signatures in presence of two witnesses.

ALBERT G. MURPHY.

LOUIS L. HALBERSTADT.

Witnesses:

HOWARD L. JONES,
JNO. P. BARRY.
